UNITED STATES PATENT OFFICE.

BEN M. HAMLIN, OF CHICAGO, ILLINOIS, ASSIGNOR TO J. V. MEYERING TRUNK COMPANY, OF CHICAGO, ILLINOIS, A CORPORATION OF ILLINOIS.

DUST-CURTAIN FOR WARDROBE-TRUNKS.

1,365,098.

Specification of Letters Patent. Patented Jan. 11, 1921.

Application filed October 8, 1920. Serial No. 415,482.

To all whom it may concern:

Be it known that I, BEN M. HAMLIN, a citizen of the United States, and a resident of Chicago, Cook county, and State of Illinois, have invented certain new and useful Improvements in Dust-Curtains for Wardrobe-Trunks, of which the following is declared to be a full, clear, and exact description.

10 This invention relates to dust curtains for wardrobe trunks and its principal object is to provide a curtain for the clothes section of a wardrobe trunk arranged to close the open side of said section and provided with 15 means for holding it stretched tightly across said opening, so as to present a neat and attractive appearance to that section of the trunk when the two trunk sections are left standing open. The invention consists in 20 the several novel features hereinafter fully set forth and claimed.

The invention is clearly illustrated in the accompanying drawing, in which:—

Figure 1 is a perspective view of a wardrobe trunk, showing a simple form of the present invention applied thereto, the curtain being partly broken away; Fig. 2 is a vertical cross section taken on the line 2—2 of Fig. 1 and Fig. 3 is a rear elevation of 30 the curtain.

Referring to said drawing, the reference character 10 designates a wardrobe trunk of ordinary construction, comprising the garment section 11 and the drawer section 12 35 hinged together and provided with locking mechanism as is customary. The clothes section is shown as having the usual hinged top 13, and shoe box 14. Clothes hangers and their fixtures (not shown) are provided, 40 as usual, in the clothes section for suspending the clothes thereon. When trunks unprovided with my curtain device are left standing open, and also during transit, dust collects in the wardrobe section and gathers 45 on the clothes. My curtain is designed to close said section against the entrance of dust, whether the trunk is left closed or open.

The curtain 15, preferably made of flexible material such as cloth, canvas or the like, is secured along its upper edge to the front edge of the top 13, and preferably a strip 16 is employed to securely fasten it in place.

The upper edge portion of the curtain is 55 placed between the strip 16 and lower side of the top 13, and the strip and curtain fastened in place by screws, tacks or like fastenings 17. The curtain may be made of single or double thickness of material, and 60 I have preferred to make it of double thickness to more effectively guard against the passage of dust.

The curtain extends across the full width of the trunk opening of the garment section and down below the top of the shoe box 14, so as to cover the entire open front of the garment section and thereby protect the garments.

A strip or bar of stiff material 18 is secured to the curtain 15 at a place above and adjacent the top of the shoe box, and when a double material curtain is used, said strip 18 is placed in a pocket 19 of the curtain, which is formed by stitching together 70 the two pieces 20, 21 of the curtain crosswise at the two places indicated by the reference character 22, 23. Coiled tension springs 24 are secured to said strip 18 on the inner side of the curtain and said 75 springs depend or extend downward and are secured to a strip 25, to which are secured loops 26, that are arranged to be fastened upon hooks 27 secured to the outer side of the shoe box adjacent its upper end. With 80 the use of the springs for the loops, the curtain is held taut when the loops are secured on the hooks, thus presenting a smooth, neat and attractive appearance to 85 the garment section, and effectively closing 90 the opening thereof and preventing dust from blowing in on the garments contained therein.

To gain access to the clothes section after it has been swung open, the loops 26 are detached from the hooks 27, and the curtain folded or swung up and back over the top 13.

It is to be observed that the curtain occupies very little space and does not interfere 100 with any of the standard parts or trunk equipment. It is simple in construction and is easily manipulated. It is not liable to get out of order due to any of the rough usage to which trunks are put. In case any unusual 105 strains are placed on the trunk, there is no danger of the curtain becoming ripped or torn, because it can yield under the influence

of the springs which enter into the construction of the means that secure it in place.

More or less variation of the exact details 5 of construction is possible without departing from the spirit of this invention; I desire, therefore, not to limit myself to the exact form of the construction shown and described, but intend, in the following 10 claims, to point out all of the invention disclosed herein.

I claim as new and desire to secure by Letters Patent:

1. In a wardrobe trunk, having a garment 15 section, a curtain secured to the top of said section adjacent its forward edge, hooks secured to a member of said clothes section therebelow, and loops secured to said curtain and adapted to be secured upon said 20 hooks.

2. In a wardrobe trunk having a garment section, a curtain secured to the top of said section adjacent its forward edge, a transverse reinforcement strip secured to said 25 curtain adjacent its lower edge, loops, resilient connections between said loops and reinforcement strip, and hooks adjacent the bottom of said section upon which said loops are detachably secured.

3. In a wardrobe trunk having a garment section, a curtain secured to the top of

said section adjacent its forward edge, a transverse reinforcement strip secured to said curtain adjacent its lower edge, there being a portion of said curtain extending 35 below said strip, coiled tension springs secured to said reinforcement strip, a second strip secured to said springs and located behind said portion of the curtain which extends below the reinforcement strip, loops 40 secured to said second named strip, and hooks fastened to a member of said garment section with which said loops are arranged to engage to hold the curtain in place.

4. In a wardrobe trunk having a garment section, provided with a hinged top and with a shoe box at its lower end, a curtain secured to the top of said section adjacent its forward edge, a transverse reinforcement strip secured to said curtain adjacent its lower edge, there being a portion 45 of said curtain extending below the top of said shoe box, coiled tension springs secured to said reinforcement strip, a second strip secured to said springs and located behind 50 a portion of the curtain which extends below the reinforcement strip, loops secured to said second named strip, and hooks fastened to said shoe box of said garment section, said loops being arranged to engage said 55 hooks to hold the curtain in place.

BEN M. HAMLIN.
